KARL PAHL, OF HEIDELBERG, GERMANY.

METAL SHEET PILING.

Application filed December 31, 1925, Serial No. 78,611, and in Germany December 7, 1925.

An important point in the construction of sheet piling is the interconnection or interlocking of the individual pile members because, although the joints must be as nearly watertight as possible, they must cause a minimum of friction during the operation of ramming.

Now, in rolling the members, it is practically impossible to make the jointing surfaces so mathematically level as to ensure accurate surface contact when the members are assembled. Difficulties therefore arise in ramming, since the members of the piling lock together in some places whereas in others there is too much free play, so that effective connection is altogether impossible.

The present invention obviates these drawbacks by applying the principle of point contact or linear contact.

20 A typical embodiment of metal sheet piling in accordance with this principle is illustrated on the accompanying drawing whereon:—

Fig. 1 is a fragmentary plan, partly in section, of the piling; and

25 Fig. 2 is a section, to a larger scale, of one of the locking joints.

Each locking joint is formed with concave or recessed walls, as shown, whereby 30 cavities *a*, *b*, *c* are produced and contact occurs only at the points *d*, *e*, *f*, *g*. As a result of the cavities, the pile members fit together, that is, can be rammed, easily. On the other hand, an efficient joint is always 35 obtained, and the members cannot twist out of engagement.

The cavities fill up with compressed soil, or the like, in the ramming operation, and this material forms a packing. When ramming in water, clay or like material can be applied on the side facing the water, and will be flushed into the leaky places by the eddies. The shape of the cavities causes 40 differences in the rate of flow, thus favouring the operation.

The stress on the joint will diminish with the friction, that is with the resistance set up in penetrating the ground, and therefore in ramming. In order to obtain the most

favourable relation between thickness of 50 material and capacity to withstand resistance pressure of the ground, it is advisable, when the herein described connecting means are employed, to replace the usual sheet pile members by light steel members of increased 55 strength and higher elongation limit, such as material containing, for example, 0.25-0.30% C, 0.7-0.8% Mn, and traces of Si, the sulphur and phosphorus content being normal. Such material does not cost ap- 60 preciably more than ordinary mild steel, but is better adapted to stand ramming and more easily transported, being stronger and lighter.

Having now particularly described and 65 ascertained the nature of my said invention and in what manner the same is to be performed, I declare that what I claim is:—

1. Metal sheet piling comprising individual pile members, interlocking jointing members on the inner edges of adjacent pile members having rigidly engaged portions for preventing a relative rotation of the pile members, the rigidly engaged portions having concaved surfaces facing each other in 70 such a manner that the rigidly engaged portions of the jointing members interlocking each other have a linear contact throughout.

2. Metal sheet piling as claimed in claim 1, wherein the jointing members on the pile members include double bent flanges with recessed contact surfaces at the bends of the flanges, and the flanges of one member when interlocked with the flanges of the adjacent 75 member forming cavities in the interlocked joint.

3. Metal sheet piling as claimed in claim 1, wherein the jointing members include double bent flanges formed integral with the adjacent members, the outer part of each double flange being substantially triangular in section, and the other part of said flange having inner walls, substantially as and for the purposes set forth.

95 In testimony whereof I affix my signature.

KARL PAHL.
